UNITED STATES PATENT OFFICE.

FRANCIS RITCHIE, OF TROY, NEW YORK, ASSIGNOR TO ISAAC A. SHEPPARD, FRANKLIN L. SHEPPARD, AND HOWARD R. SHEPPARD, ALL OF PHILADELPHIA, PENNSYLVANIA.

DESIGN FOR A HEATING-STOVE.

SPECIFICATION forming part of Design No. 20,973, dated July 28, 1891.

Application filed July 1, 1891. Serial No. 398,185. Term of patent 7 years.

To all whom it may concern:

Be it known that I, FRANCIS RITCHIE, a citizen of the United States, and a resident of Troy, Rensselaer county, New York, have invented a Design for a Dwarf Stove, of which the following is a specification.

My design for a heating-stove for burning either wood or coal is clearly illustrated in the accompanying drawing, in which the stove is shown in perspective. The stove is of the class known as "dwarf heaters," and has a base, a body, and a top, as shown.

The main feature of the design is the C-scroll. The doors of the front plate each have two C-scrolls which are arranged back to back, united by a rosette. The ventilating-section on the ash-pit door is bordered by bead-work. On the side door is a combination of the design shown on the doors of the front plate. In place of two C-scrolls there are four scrolls joined together by rosettes, form-

ing a diamond center. Between this side door and the top on the side plates are two S-scrolls. The C-scroll design is also found on each foot of the stove. The top of the stove has an elongated dome of open-work in which the double-C-scroll design is carried out to correspond with the design on the doors of the stove, and on this dome is an urn, which is in keeping with the design of the rest of the stove.

I claim—

The design for a dwarf heating-stove, as herein described, and shown in the accompanying drawing.

In testimony whereof I have signed my name to this specification in the presence of two subscribing witnesses.

FRANCIS RITCHIE.
